UNITED STATES PATENT OFFICE.

SWEN PAULSON AND ABRAM HATCH, OF HEBER, UTAH.

DEVELOPING-MACHINE.

1,381,222.

Specification of Letters Patent. Patented June 14, 1921.

Application filed February 20, 1920. Serial No. 360,192.

To all whom it may concern:

Be it known that we, SWEN PAULSON and ABRAM HATCH, citizens of the United States, residing at Heber, in the county of Wasatch 5 and State of Utah, have invented certain new and useful Improvements in Developing-Machines, of which the following is a specification.

This invention relates to an improved machine for developing photographic films and has as one of its principal objects to provide a simple machine of this character which will efficiently operate to develop one or more films, as may be desired, uniformly.

15 The invention has as a further object to provide a developing machine employing a drum for receiving the films and wherein a developing tank will be provided for immersing the films as the drum is rotated.

20 And the invention has as a still further object to provide a machine wherein the tank may be lowered away from the drum so as to permit the films to be mounted thereon and may then again be easily raised to 25 active position for submerging the lower portion of the drum.

Other and incidental objects will appear hereinafter.

In the drawings:

30 Figure 1 is a side elevation of our improved machine,

Fig. 2 is a sectional view on the line 2—2 of Fig. 1, and looking in the direction of the arrows,

35 Fig. 3 is a fragmentary transverse section taken medially through the device.

Fig. 4 is a side elevation of the developing tank employed and its elevating mechanism, and

40 Fig. 5 is a perspective view showing the elevating mechanism for the tank in detail.

In carrying the invention into effect, we employ a supporting frame or stand 10. This stand may be constructed of any approved material and journaled upon the end portions of the stand is the shaft 11 of a film receiving drum 12. The exterior surface of the drum is of such character that thumb tacks or other approved fastenings 45 may be driven into the drum. Fixed upon the shaft 11 at one end thereof is a drive wheel 13 and frictionally coacting with this drive wheel is the drive pulley 14 of a motor 15, the motor being conventionally shown. 55 An electric or other approved type of motor may be employed. The motor is sup-

ported by a shelf 16 which extends laterally from the adjacent end of the stand.

For immersing the lower portion of the drum we employ a trough shaped developer 60 tank 17. This tank may be constructed of sheet metal or other approved material and is provided at its sides with longitudinal overhanging flanges 18. Depending from the tank at one end thereof is a waste pipe 65 19 in which is interposed a shut off valve 20 and positioned upon the lower longitudinal bars of the stand beneath the waste pipe is a vessel 21. In connection with the developer tank, we employ an elevating mechanism. Seated upon the upper longitudinal bars of the stand are pairs of oppositely disposed bearing blocks 22 and journaled in the blocks of each pair is a transverse shaft 23. The intermediate portions of 70 these shafts are, as particularly shown in Figs. 3 and 5, bowed downwardly to clear the tank when the tank is lowered. Fixed to the shafts 23 are pairs of arms 24, one of which is elongated to provide an operating 75 lever 25. Connecting corresponding arms of said pairs are coupling rods 26 and mounted upon the arms at their upper ends are rollers 27 engaging beneath the flanges 18 of the tank for supporting the tank. Depending from the tank at one end thereof is a lug 28 and pivotally connected at one end to this lug is a stay rod 29, the opposite end of which is pivotally connected to a cross rod 30 extending between the pair of legs of the 80 stand adjacent the opposite end of the tank. Thus, this rod will hold the tank against longitudinal movement so that the handle 25 may be swung for elevating the tank to active position as shown in Figs. 2 and 3 or 85 for lowering the tank to inactive position as shown in dotted lines in Fig. 4.

In use, the tank 17 is first filled with cold water when the tank is elevated to immerse the lower portion of the drum 12. The films 100 to be developed are then, after having preferably been first soaked so as to render the film strips limp and pliable, helically wound upon the drum 12, the films being secured to the drum by thumb tacks or other approved fastenings driven into the drum and the convolutions thereof being arranged edge to edge. As the drum is turned, incident to the placing of the films thereon, the films will be turned through the cold 110 water bath in the tank for keeping the films wet so that when the operation of placing

- all of the films desired upon the drum is completed, the tank may be lowered and the water therein drained through the pipe 19 into the vessel 21. After closing the shut off valve 20, the developer is then introduced into the tank when the tank is again raised into active position. The motor 15 is then started for slowly revolving the drum and turning the films thereon through the developer bath. Thus, the entire surface of all of the films will, as the drum turns, be immersed for uniformly developing the films. Upon the completion of the developing operation, the developer is drained off and a bath of cold water again introduced into the tank for washing the films, turning of the drum through the water bath serving, of course, to effectually remove all of the developer therefrom. The films may then be removed from the drum and placed in a fixing bath. It will accordingly be seen that we provide a particularly efficient type of machine and a machine which may be easily operated.
- Having thus described the invention, what is claimed as new is:
1. A developing machine including a supporting frame, a film receiving drum journaled thereon, pivoted tank supporting arms carried by the frame, a tank carried by said arms, and means holding the tank against swinging movement with the arms, the arms being operable for elevating the tank whereby a portion of the drum may be immersed.
  2. A developing machine including a supporting frame, a film receiving drum journaled thereon, shafts journaled on the frame,
- arms fixed to said shafts, a tank supported by said arms, and means coupling certain of the arms, the arms being movable for elevating the tank whereby a portion of the drum may be immersed.
3. A developing machine including a supporting frame, a film receiving drum journaled thereon, pivoted tank supporting means carried by the frame, a tank freely resting on said means, and a stay rod extending between the tank and frame for holding the tank against endwise movement, the tank supporting means being operable for elevating the tank whereby a portion of the drum may be immersed.
4. A developing machine including a supporting frame, a film receiving drum journaled thereon, a tank, pivoted elevating means for the tank, and means securing the tank against pivotal movement with said elevating means whereby when said elevating means is rocked to coact with the tank, the tank will be raised for immersing a portion of the drum.
5. A developing machine including a supporting frame, a film receiving drum journaled thereon, a tank having lateral flanges, arms pivoted upon the frame and having rollers to coact with said flanges, and means holding the tank against swinging movement with the arms whereby the arms may be rocked for elevating the tank to immerse a portion of the drum.

In testimony whereof we affix our signatures.

SWEN PAULSON. [L. S.]
ABRAM HATCH. [L. S.]
